UNITED STATES PATENT OFFICE.

EUGÈNE CHARLES ISIDORE CAILLIEZ, OF LENS, FRANCE.

APPLICATION OF ELECTRIC LIGHTS TO REVOLVERS OR OTHER FIREARMS.

SPECIFICATION forming part of Letters Patent No. 794,924, dated July 18, 1905.

Application filed January 6, 1904. Serial No. 187,960.

To all whom it may concern:

Be it known that I, EUGÈNE CHARLES ISIDORE CAILLIEZ, a citizen of the Republic of France, and a resident of Lens, France, have 5 invented certain new and useful Improvements in the Application of Electric Lights to Revolvers or other Firearms, of which the following is a specification.

The present invention refers to improvements in the construction of firearms, permitting them to be used during night-time or in darkness.

It essentially consists in the adaptation of an electric lamp with a reflector at the end of 15 the barrel in connection with a battery or source of electricity situated, preferably, in the butt, which can be instantly lighted by means of a contact placed on the handle and closing the circuit. This application can be 20 adapted to all kinds of firearms, but is especially designed for those used for personal defense, destined for firing at short distances. It reveals the object aimed at before firing, at 25 the same time leaving the marksman in complete obscurity. If used against a malefactor who succeeds in escaping, at least his features have been seen.

I will now describe my invention as applied to a revolver and by reference to the accompanying drawings, in which—

Figure 1 is a side elevation of a revolver fitted with my invention. Fig. 2 is a longitudinal section of the revolver shown in Fig. 1. Fig. 3 is an end view of the cartridge-chamber. Fig. 4 is a plan view of the battery or cells and their receptacles. Fig. 5 is a side view of a gun fitted with my invention. Fig. 6 shows certain improvements connected with the mechanism of a hammerless revolver.

Referring to Figs. 1, 2, and 3, the butt *a*, the frame *b* of the chamber, and the barrel *c* are made in one piece. The chamber *d* has holes *f*, as well as sockets *e*, for the cartridges. These holes *f* receive the safety-pin *g*. In the 45 center of the chamber *d* a hole *h* is formed, through which passes the spindle *i*, around which the chamber turns. This spindle *i* is hollow, having a socket *k*, forming a reflector

l. Into the socket *k* is screwed or fitted in any suitable manner an incandescent electric 50 lamp *m*, its wires *n* for conducting the necessary electric current passing through the interior of the hollow spindle *i*, which is attached at its back extremity to the frame *b* of the chamber. These wires *n* end in two closed 55 isolated passages attached to the extremity of the spindle *i* and are prolonged to a terminal *o*, kept insulated on a plate *p*, which separates the box of the mechanism from the butt *a*. The latter serves as a receptacle for the battery or cells. The negative pole is in constant contact with the terminal *o* by the intermediary of a plate *s*, and the positive pole is near to a spring-controlled plate *t*, to which is attached an exterior button *u*. On pressing on 60 this button and plate the positive pole transmits the current to the terminal *o* and the circuit is closed, the lamp lights, and illuminates the object aimed at. If the button *u* is released, the plate *t* leaves the positive pole and 65 the terminal and the lamp goes out. The bottom *v* of the butt is removable to permit of the introduction or replacing of cells. A ring *w* is fixed to its center, which permits of its being easily unscrewed from the butt. In the 70 revolver represented in the accompanying drawings if the trigger *x* is pressed in the direction of the arrow the spring *y* is compressed. Then the finger or part *z* is raised, which causes the ratchet-wheel *a*, firmly attached to the chamber *d*, to turn the distance 75 of one tooth. The lever *b'*, with a jointed heel-piece *c'*, is then moved, and at the same time by means of the projection *d'* of the trigger the part *e'* is operated. In this movement 80 the lever *b'*, engaged in the socket *g'*, causes the striker to be drawn back, this movement compressing a spring-coil *h'*. The striker and its spring are situated in a tube *i'*, having a slot *k'* underneath to permit the movement of 85 the lever *b'*. At a given moment the jointed heel-piece *c'* of the lever *b'* escapes from the beak *l'* of the trigger. The spring *h'* being thus free to act causes the striker to hit the cartridge. The beak *l'*, which has passed in front 90 of the heel-piece *c'*, is returned by the spring

y, causing the heel to turn backward, and thus retake its position for the following shot, as is shown in Fig. 2.

What I claim, and desire to secure by Letters Patent, is—

In combination with a revolver having a spindle for the cylinder formed hollow, an electric light arranged at the front end of the spindle, means for generating an electric current arranged in the handle of the revolver,

circuit connections extending through the spindle and means for closing the circuit, substantially as described.

In testimony that I claim the foregoing I have hereunto set my hand this 18th day of 15 December, 1903.

EUGÈNE CHARLES ISIDORE CAILLIEZ.
